UNITED STATES PATENT OFFICE.

EDWARD A. TUTTLE, OF NEW YORK, N. Y.

DESIGN FOR A CIRCULAR REGISTER.

Specification forming part of Design No. 5,469, dated January 9, 1872.

Specification describing a new and original Design for a Circular Register, invented by EDWARD A. TUTTLE, of the city of New York, in the county and State of New York.

The accompanying photographic illustration fully represents my new design.

The design consists of a novel collection and arrangement of arabesques within a circular border or rim and around a central rosette,

and of the combination therewith of eight, more or less, garlands or ornamental arches, *a a*, as shown.

I claim as my invention—

The design for a circular register, as shown.
EDWARD A. TUTTLE.
